UNITED STATES PATENT OFFICE.

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed September 25, 1922. Serial No. 590,372.

This invention relates to cash registers, and especially to improvements in the type of machine shown in a co-pending application for Letters Patent of the United States 5 of Edward J. Von Pein, Serial No. 293,141, filed April 28, 1919.

Among the objects of this invention are the provision of mechanism for positively setting up total type, total indicators, and 10 for effecting such setting up operation of the type and indicators simultaneously.

Another object is the provision of mechanism for positively returning the total type and indicators to zero at the beginning of 15 each total-taking operation.

With these and incidental objects in view, the invention consists of certain novel features of construction and combinations of parts, the essential elements of which are set 20 forth in appended claims and a preferred form of embodiment of which is hereinafter described with reference to the drawings which accompany and form part of this specification.

25 Fig. 1 is a plan view of a part of the machine showing the totalizer and printing means.

Fig. 2 is an elevation of the printing mechanism.

30 Fig. 3 is a section taken on line 3—3 of Fig. 1.

Fig. 4 is a section taken on line 4—4 of Fig. 1, with a part of the right hand side of the totalizer broken away.

35 Fig. 5 is a partial view of the mechanism for driving the cam shaft.

Fig. 6 is a detail view of a part of the turn-to-zero mechanism.

40 Fig. 7 is a detail view of the cam for rocking the total-taking connecting gears into mesh with gears of the totalizer.

Fig. 8 is a detail view of the cam for restoring the printing and indicating mechanism to zero.

45 Fig. 9 is a detail view of the date and consecutive number cylinder.

Fig. 10 is an illustration of the receipt issued by the machine.

50 Fig. 11 is an illustration of a section of the record strip.

Fig. 12 is a detail view of the cam for operating the alining mechanism.

Fig. 13 is a detail view of the cams for feeding the itemized receipt.

The machine disclosed comprises three 55 groups of amount keys 30, approximately only one-half of the key-board however being shown in Fig. 1. These keys are pivoted on a transverse rod supported in the side frame members of the machine and at their 60 rear ends bear against a key coupler 31 with which they cooperate in the usual manner.

The rear ends of the keys support item indicators 32, and also uprights 35 which are notched to cooperate with rods on rocker 65 members 36 supported on a shaft 37 to move said members proportionate to the number of units represented by the keys depressed.

Totalizer actuators 40 are operated by these rockers, the units actuator being directly secured to its rocker, which is free to rock about the shaft 37. The dimes rocker and actuator are pinned to the shaft 37. The dollars actuator is driven by a pinion 41 fixed to a shaft 42 which is driven by a 70 pinion and segment from the dollars rocker (not shown). This method of connecting the higher order rockers with their actuators is old and well known in the art and is shown in connection with the tens of dollars 75 actuator and rocker in United States patent to Cleal No. 998,602.

The units totalizer actuator cooperates with a pinion 45 secured to a shaft 46 upon which the units type wheel is mounted. The 80 item type wheels are generally designated by the numeral 47 (Fig. 2). The dimes type wheel is set up by means of a segment 48 pinned to the shaft 37 and meshing with a pinion 49 on a tube 50 (see also Fig. 3) supporting said type wheel. Pinned to the shaft 42 which controls the dollars totalizer actuator is a pinion 51 in mesh with a segment 52 free on the shaft 37 and in mesh with a pinion 53 on a tube 54 to which the dollars type wheel is secured. By means of the mechanism so far described, the item type wheels are adjusted to print the amount represented by the keys depressed.

A cam shaft 60 (Fig. 5) which constitutes the main driving shaft is given one rotation during each item-entering operation of the machine. A pinion 61 secured thereto is driven from a double rack 62 guided on a

stud 63. This rack is driven from the key coupler by means of a stud 64 projecting from the key coupler into a slot in the rack and is thrown alternately into mesh with the pinion 61 by a spring 65 and a spring-pressed pawl 66. A flange 67 on the rack cooperates with a flange 68 on the machine frame to hold the rack and pinion in mesh during up-and-down movement of the rack.

10 The right hand end of the shaft 60 (Fig. 3) carries a cam 70 which cooperates with a spring actuated arm 71 curved through the printer frame 73 and provided with a platen 72 (Fig. 2) for taking impressions from the item type wheels. The spring actuating the arm 71 is supported on one end of an adjusting lever 87 (Figs. 2 and 3) secured to the printer frame 73 by screws one of which extends into a slot in the lever, the other being screwed into the lever and supported in an eccentric 88 mounted in the printer frame.

15 The issuing receipt strip is fed during item printing operations by mechanism actuated from the key coupler. This mechanism comprises a key coupler trunnion 75 (Fig. 2) which extends through the printer frame 73. An arm 76 (Figs. 2 and 3) is pinned to the trunnion inside of the frame and carries a pin 77 extending through a slot in the frame into an arm 78 loosely supported on the trunnion outside of the frame. The arm 78 is held on the trunnion by a clip 79 engaging a groove in a hub rigid with said arm, as indicated in Fig. 2. The arm 78 drives a pawl 80 which co-operates with a ratchet 81 rigid with a feed roller 82 secured to a shaft 83. A tension roller 84 holds an issuing receipt strip 85 in feeding engagement with the feed roller 82. The strip 85 is fed from a supply roll 86. Also operated from the arm 78 is a link 90 connected to an arm 91 which operates a feed roller 92 for an inking ribbon in a well known manner. The inking ribbon passes between the item type wheels and issuing strip and in cooperative relation with total type wheels later referred to.

20 The totalizer comprises elements (Fig. 4) mounted upon a turn-to-zero shaft 101. Each of these elements comprises a pinion 100 adapted to move into mesh with a totalizer actuator 40. In addition the element comprises a ratchet wheel, and a transfer tooth 102 for cooperation with a transfer pawl supporting arm 103 controlling the position of pawl 104 which is operated by a transfer arm 105 operated from a cam 106 secured to the cam shaft 60. Tripping of the pawls 104 during turn-to-zero operations is prevented by arms 107 carried by a shaft 60 operated by an arm 108 (Fig. 1) actuated by a cam 109 secured to the turn-to-zero shaft 101.

25 The totalizer is supported in a frame 110 pivoted at 111 and rocked into engagement with the actuators by a bifurcated arm 112

which carries rollers cooperating with a cam 113 secured to the shaft 60.

30 Each of the totalizer elements is also provided with a gear 114 which meshes with a gear 115 carried on a rod supported in the totalizer frame. During a totalizing operation, which will be set forth later, the cam 113 functions to hold the totalizer frame and gear 115 against bodily movement about the pivot 111.

Total printing and indicating mechanism.

35 Total type wheels 120 (Fig. 2) are connected by a tube line 121 (Fig. 3) with pinions 122 in mesh with segment gears 123 loosely supported on a shaft 124. Integral with segment gears 123 are segment gears 125 in mesh with gears 126 connected by a tube line 127 with gears 128, said tube line being supported on a rod 129 carried by a bracket 130 and the printer frame 73. Gears 133 in mesh with gears 128 (Figs. 1 and 4) are mounted on a rod 134 supported in an arm 135 pivoted on the rod 129 and in an arm of a lever 136 (Fig. 3) also pivoted on said rod. The movements of said lever are controlled by a pitman 137 and a box cam 138 (Fig. 7) to engage the gears 133 with the gears 115 at the proper time during a total-taking operation. The pitman is bifurcated to straddle a shaft 164 to which the cam is secured and carries a roller 139 cooperating with said cam.

40 The segment gears 125 also control the position of the indicators through segment-gears 140 rigidly connected thereto. The segment-gears 140 mesh with segment-gears 141 in mesh with segment-gears 142 integral with segment-gears 143 in mesh with pinions 144 on a shaft 145. The pinion 144 of the units order is secured to the shaft 145 upon which left and right hand total indicators 146 (see also Fig. 1) are pinned. The pinions of the other orders are rigid with gears 147 rotatably supported on the shaft 145 and in mesh with gears 150 secured on the shafts 151 to which pinions 152 (see also Fig. 4) are secured which mesh with gears 153 on the left and right total indicators.

45 The segment-gears 142 and 143 (Fig. 3) are aligned by alining means 160 with which cooperate spring-pressed alining pawls 161 actuated by a pitman 162 controlled by a cam 163 secured to a shaft 164 (see also Fig. 12). The shaft 164 (Fig. 3) receives its rotation from a gear 165 secured thereto and in mesh with a gear 166 secured to a shaft 167 which carries a gear 168 (Fig. 2) in mesh with a gear 169 driven from any suitable operating means.

50 The total type wheels and total indicators are returned to zero at the beginning of a total-taking operation by a yoke 170 (Fig. 3) provided with an arm 171 operated by a pitman 172 whose movements are controlled

by a cam arm 173 (Fig. 8) fixed on the shaft 164. The zero position of the total type wheels and total indicators is determined by the stop bar 174 with which the yoke 170 cooperates.

The cams 163, 173 and 138 are timed to operate in the order named to throw out the aliners 161, to return the total type wheels and total indicators to zero, and to engage the gears 133 with the gears 115. When the gears are so engaged the totalizer is turned to zero and the total type wheels and total indicators adjusted by means of cams 180 (Fig. 3), secured to the shaft 167, a rocker 181 provided with rollers cooperating with said cams, and a link 182 connecting the rocker with a segment-gear lever 183 (Figs. 2 and 6) secured on a shaft 184 and in mesh with a partial gear 185 pinned to the shaft 124. Also pinned to the shaft 124 is a segment-gear 186 in mesh with a gear 187 which carries a spring-pressed pawl 188 cooperating with a ratchet 189 integral with a gear supported co-axially with and of the same size as gear 187 and in mesh with a pinion 190 secured to a shaft connected to the turn-to-zero shaft 101 by a universal short shaft portion 191 (Fig. 1) connected to the cam 109. This connection permits proper movement of the totalizer frame during item entering operations.

As the segment-gear lever 183 (Fig. 6) rocks first clockwise and then counter-clockwise back to home position, it rocks the shaft 184 likewise and through arm 195 (Fig. 3) and link 196 moves a flash 197 from its home position to a horizontal position to cover the indicators as they are adjusted and then back to the position shown in Fig. 3. The flash is pivotally supported on shaft 145.

Each total-taking operation is registered on a consecutive numbering device which is operated by a lever 200 bifurcated at one end to receive a pin 201 on the link 182 and provided at its other end with a pin 202 (see also Fig. 9) cooperating with the bifurcation in an arm 203 mounted on a stud 205 in the printer frame 73. The arm 203 is connected by a pin 206 with a yoke 207 actuating a differentially timed pawl to operate the consecutive numbering type wheels. The consecutive counter barrel also supports date type wheels 208 adjusted by sleeves 209 in a well known manner. The consecutive numbering device may be turned to zero by means of a knob 204.

Impressions are taken upon the issuing strip from the consecutive numbering and date wheels, the total type wheels and electros 210 and 211 to print a receipt as shown in Fig. 10 by an impression means 212 supported by an arm connected to a lever 213, one end of which cooperates with a box cam 214 fixed on the shaft 167, timed to operate

after the total and consecutive numbering type wheels have been set.

Impressions from the total type wheels may also be taken upon a detail strip 217 (Figs. 2 and 11) by a hammer 218 operated from the lever 213 by a link 219. Any suitable means may be provided to operate the receiving roll 220 for the detail strip during total taking operations.

After the impressions are made the issuing strip is fed out of the machine a sufficient distance to move the printed total amount beyond the knife edge. For the accomplishment of this function the shaft 83 of the feeding roller 82 carries a ratchet 225 (Fig. 3) operated by a pawl 226 carried by a plate 227 rigid with a gear 228 operated by a segment-gear 229. The segment-gear 229 is provided with a slot 230 which receives a roller 231 (Fig. 13) carried by a rocker 232 cooperating with cams 233 secured on the shaft 167. The cams are timed to feed the issuing strip after the impressions have been made.

The gears 133 are disengaged from the gears 115 after the totalizer elements have been turned to zero and the total type and total indicator wheels adjusted. At this time the aliners 161 are moved back into alining position.

Operation.

The item amounts are indicated, accumulated and printed by operation of appropriate keys by mechanism all old in the art. The impression is taken upon a detail strip which is fed out of the machine as the items are registered. After all of the items involved in a transaction have been registered, the drive shaft 167 (Fig. 2) is actuated by a crank or any other suitable means. By mechanism previously described, operation of this shaft disengages the aliner 161 (Fig. 3) from the indicator alining segment, permitting the indicators and total type elements to be returned to home position by the bail or yoke 170 actuated by a pitman 172 operated from the cam shown in Fig. 8. The connecting gears 133 are then moved into mesh with the gears 115 (Fig. 4) by a pitman (Fig. 3) operated by the cam shown in Fig. 7. The rocker 181 (Fig. 3), which in the meantime had been rocked clockwise, is now moved counter-clockwise, thereby actuating the pawl 188 by mechanism shown in Figs. 3 and 6 to rotate the turn-to-zero shaft 101 (Fig. 4). This rotates the totalizer elements to zero and through a train of gears shown in Fig. 3 moves the total type elements and indicators an amount proportionate to the amount on the totalizer, thereby setting up the total on the total type and indicator elements. The amount accumulated on the totalizer during the item registration now appears on the indicators

4
and on the type wheels at the printing lines. The upper and lower impression members (Fig. 2) are then operated as the rotation of the shaft 167 is continued, making an imprint of the total on the detail strip and on the issuing receipt strip 85. Continued rotation of the shaft 167 causes the receipt strip to be fed to the left until the total impression has passed the severing edge 221. When the machine is at rest, the portion of the strip fed out of the machine is torn off and is handed to the customer as a receipt. This receipt bears information as shown in Fig. 10.

15 While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

What is claimed is:—

25 1. The combination of a totalizer movable from home position to receive items, means to hold the totalizer in home position for total printing operations, total printing devices, and means movable into mesh with said 30 totalizer for setting the amounts on the total printing devices as the totalizer is turned to zero.

2. The combination of a totalizer movable to receive items, elements adapted to be set up in accordance with the amounts in the 35 totalizer, means adapted to be driven by the totalizer for effecting a setting up operation of said elements, said means being movably mounted to move into engagement with the totalizer in home position, and means 40 for turning the totalizer to zero.

3. The combination of a totalizer mounted for movement away from home position to receive items, means movable into engagement 45 with the elements of the totalizer in home position to set up other elements in accordance with the amounts in the totalizer as the totalizer is turned to zero, a turn-to-zero shaft for said totalizer, and means for operating said shaft.

4. The combination of a totalizer mounted for movement from home position to receive items, means for transferring an amount from said totalizer to another accounting device, said means comprising toothed members 55 normally disengaged from but adapted to be engaged with the elements of the totalizer, means for positively moving said members to their home position before they are engaged with the elements of the totalizer, and means for holding said totalizer in home position during a transferring operation.

5. The combination of a totalizer, total indicators normally held in a previously ad-

justed position, an operating connection between the indicators and totalizer normally disengaged from the totalizer, and means for first moving said indicators to zero, engaging said connection with the totalizer, and then turning said totalizer to zero and simultaneously adjusting said indicators to show the amount taken from the totalizer.

6. The combination of total indicators, a totalizer, means adapted to be engaged with the totalizer to be operated thereby for adjusting the indicators, positive means for turning said indicators to zero before said first mentioned means is engaged with the totalizer, and means for turning said totalizer to zero and through said first mentioned means to adjust said indicators.

7. In a machine of the class described, the combination of a totalizer, total printing elements, impression means, a record strip, means for moving said elements to zero, means connected with said elements for adjusting the same involving members adapted to be driven by the totalizer, means for turning the totalizer to zero and adjusting the printing elements through said adjusting means, means for operating the impression means, and means for feeding the strip after an impression has been made.

8. The combination of a totalizer, total type elements, means normally disengaged from said totalizer adapted to engage said totalizer and be driven thereby for adjusting said type elements, means for turning said totalizer to zero to adjust the type elements, means for taking an impression from said type elements, and means for feeding the receiving strip after the impression has been made.

9. The combination of a totalizer, total type elements, positive means for turning said elements to zero, means for turning said totalizer to zero, and positive means operated by said totalizer as it is turned to zero for adjusting said type elements.

10. The combination of totalizer actuators, a totalizer normally disengaged therefrom, a totalizer turn-to-zero mechanism, total printing elements, and means operated by said totalizer in its normal position as it is turned to zero for adjusting said printing elements.

11. The combination of a totalizer, a turn-to-zero mechanism, an operating means therefor, total printing elements, and means actuated by said operating means for operatively connecting said totalizer with said printing elements and constituting a means for transferring movement from the totalizer to the printing elements as the turn-to-zero mechanism is operated.

12. The combination of a key operated accounting mechanism involving a totalizer adapted to be turned to zero, total printing

elements, means operatively connected to said elements and normally disconnected from said totalizer, and an operating mechanism for moving said means into engagement with said totalizer and for turning said totalizer to zero to adjust said printing elements.

13. The combination of total indicators, total printing elements, a totalizer adapted to be turned to zero, positive operating connecting means between the totalizer and the total indicators and total printing elements, said means being normally disconnected from the totalizer, and an operating means for moving said connecting means into engagement with the totalizer and for turning the totalizer to zero to actuate said connecting means to adjust said indicators and printing elements.

14. The combination of a totalizer adapted to be turned to zero, total indicators, total printing elements, positive operating means for simultaneously moving said indicators and elements to zero, means positively operatively connected with said indicators and elements and movable into engagement with

said totalizer, and an operating means for operating both of said means.

15. The combination of a totalizer adapted to be turned to zero, total indicators, total printing elements, positive operating means for moving said indicators and elements to zero, means positively operatively connected with said indicators and elements and movable into engagement with said totalizer, and an operating means for operating both of said means.

16. The combination of item entering means, a totalizer and item indicators operated thereby, total indicators, and positive operating means independent of said item entering means for adjusting the total indicators to indicate the amount in the totalizer.

17. The combination of item entering means, a totalizer and item printing elements operated thereby, total printing elements, and positive operating means independent of said item entering means for adjusting the total printing elements to print the amount in the totalizer.

In testimony whereof I affix my signature.
EDWARD J. VON PEIN.
